APPARATUS FOR REMOVING NONCONDENSIBLE GASES FROM REFRIGERATING SYSTEMS

John F. Weaver, Dallas, Tex.

Application November 3, 1934, Serial No. 751,432

1 Claim. (Cl. 62—115)

This invention relates to commercial refrigeration and it has particular reference to a method and apparatus designed to purge a refrigerating system of objectionable non-condensable gases.

5 The principal object of the invention is to provide apparatus of an extremely simple and easily operated construction which is adaptable to that type of system in which ammonia is employed as the refrigerating fluid and is extremely effective in purging the system of accumulated, non-condensable gases entrained with the refrigerating fluid.

10 The invention further aims as one of its foremost objects to provide a method for the expulsion of the undesirable gases from a refrigerating system which consists primarily in establishing a refrigerating zone, in which is situated a sub-zone, in causing to pass into the sub-zone at low temperatures the refrigerating fluid with its entrained, non-condensable gases, in passing off the non-condensable gases above the fluid, in observing the fluid level in the sub-zone to determine the amount of non-condensable gases remaining in the system and in returning the condensed refrigerating fluid back to the system.

15 Still another object of the invention is to provide an apparatus and method for the purpose specified in which the refrigerating system may be purged of objectionable gases without interfering with the normal operation of the plant. Moreover, the present invention does not require a reduction in the amount of refrigerating fluid used in normal operation to accomplish its results, which is necessary in certain types of purging apparatus to maintain the suction pressure required to obtain the desired temperature.

20 With the foregoing objects as paramount, the invention has particular reference to its salient features of construction and arrangement of parts, which will become manifest as the description proceeds, taken in connection with the accompanying drawing, wherein:—

25 Figure 1 shows the invention in elevation and partly in vertical section and its relationship with the conventional type of receiver of a refrigerating system.

30 Figure 2 is an elevation of one form of thermometer well showing the manner in which it may be attached either to a closed pressure cylinder of the invention or to any adjacent suction line of the system, and

35 Figure 3 is a view on lines 3—3 on Figure 2.

35 Since refrigerating systems employing carbonic acid, ammonia and like fluids as the refrigerating medium are well known to the art, it is not

considered necessary to describe such a system. It is however important to mention that in the operation of any such refrigerating system, the results obtained or the temperature maintained, depends entirely on the suction pressure maintained. When any type of purger is put into operation requiring the expulsion of additional refrigerating fluid in order to obtain the desired temperature, the amount of such fluid will necessarily have to be reduced in order to maintain 10 the suction pressure necessary for the desired temperature, therefore, the amount of work or refrigeration which would ordinarily be produced during inoperative periods of the purger would be materially reduced. Where refrigerating fluid 15 is required to be passed through a purger to cool the same, it is impossible to utilize but a very small amount of such refrigerant, the surplus passing through and into the suction line of the system and on to the compressor, thereby reducing 20 the superheat and resulting in a considerable drop in the efficiency of the compressor.

25 The foregoing condition is likewise objectionable in that the cylinders of the compressor frequently frost over which results in undue mechanical wear and loss of power. That ammonia which passes off with the suction gases and whose refrigerating effect is greatly reduced thereby is not only detrimental to the normal operation of the system, the efficiency of the machine and 30 causing undue wear but this surplus refrigeration is a complete loss. The present invention, as previously stated, instead of being independently cooled, it is confined in an already refrigerated zone, such as an ice chamber but preferably in a brine tank and under these conditions, the amount of refrigeration utilized in refrigerating the gases is so small as to be negligible.

35 Continuing with a more detailed description of the drawing, 1 designates a brine tank for the 40 purpose of explanation, it being understood that the unit embodying the invention will function with equal efficiency when situated in a zone at low temperatures. A cylinder 2 is partially submerged in the brine and has closed ends 3. Condensed refrigerating fluid enters the pipe 4 of the receiver 5 from the condenser, not shown, and is normally passed on through the liquor line 6a to the expansion coils, not shown.

45 Under ordinary operating conditions, the non-condensable gases entrained with the fluid likewise pass with the fluid to the receiver, thereby causing excessive head pressures which are detrimental to the operation of the system in two ways. First, by increasing the power used to 50

55

operate the compressor and reducing the amount of refrigerant that could be handled by the compressor if the excessive head pressure is overcome by a means such as herein provided. However, 5 since the non-condensable gases accumulate above the liquor level in the receiver 5, due to differential temperatures, they are immediately drawn off through the pipe 6 with some ammonia gas and deposited through the pipe 7 into the sub-zone or chamber 2, it being understood that both the valves 8 and 9 are opened to carry out this 10 operation.

Manual attendance is ordinarily not required, the purger being entirely automatic, however, the 15 valve 10 in the pipe 11 being closed, the liquor entrapped within the chamber 2 cannot escape and the non-condensable gases ascending through the liquified column of refrigerating fluid is drawn off through the pipe 12, through valve 13 and released to atmosphere through the pipe 14. It 20 is desirable to provide a container, preferably transparent in which to submerge the pipe 14 in order to visibly indicate the volume of non-condensable gases escaping from the system. Ebullition of the contents of the container will definitely 25 show that gases are escaping from the system. Should the valves be opened too long or if there is but a small amount of non-condensable gases in the system, the operator may at once determine this by the distinctive odor arising from the container which has not been illustrated, and take precautions to correct the condition either by closing the valve partially or entirely.

A sight indicator 15 is provided, for communication 30 with the chamber 2 through pipes 16 and 17 controlled by valves 18 and 19. When the system is thoroughly purged, the liquor rises in the chamber 2 and may be observed in the indicator 15, whereupon the engineer closes valves 35 9 and 13 and opens valve 10 whereupon the liquor or liquified refrigerating fluid is withdrawn from the chamber 2 and is returned to the system through the pipe 11.

It is apparent from the foregoing that no loss 40 of refrigerating fluid occurs during the extraction of air and other non-condensable gases from the system.

Under certain conditions, where it is not desired to employ a sight indicator such as shown 45 at 15, a thermometer 20 may be substituted and may be affixed either to the chamber 2 or to any

part of the adjacent liquor line which may, for the purpose of illustration, be designated by the reference character 21. By employing this thermometer as indicated, an expert refrigerating engineer may determine the amount of non-condensable gases circulated in the system. 5

A novel means of supporting the thermometer relative to the line is shown in Figures 2 and 3 and is comprised of a clamp in the form of a band 22, secured to the line by a bolt 23. A pocket 10 24 is provided on the band adapted to contain ammonia oil, mercury or other suitable material having high conductive properties and to this pocket is affixed a thermometer well 25 to receive the thermometer 20. As stated, the device shown 15 in Figures 2 and 3 and just described may be substituted for the sight indicator 15 or may be used independently thereof at any point in the system where it is possible to determine by temperature tests the amount of non-condensable gases in the 20 system. It is of course obvious that undue frosting of pipes and other equipment may be used as a means for detecting air in the system but the present invention and its appurtenances are such that such a means is rendered unnecessary 25 particularly since conditions such as these incur avoidable expenses and trouble.

Manifestly, the construction shown is capable of some modification and such modification as is considered within the scope and meaning of 30 the appended claims is also considered within the spirit and intent of the invention.

What is claimed is:

In an apparatus for removing non-condensable 35 gases from refrigerating systems, the combination comprising a receiver for refrigerating fluid, a brine tank, a closed vertically disposed cylindrical chamber partially submerged in the brine in said tank and receiving fluid from said receiver, parallel pipes of substantially equal length 40 depending into said chamber whereby to introduce fluid into and discharge the same from said chamber, means above the liquid level in said chamber to effect escape of non-condensable gases accumulating in said chamber, valve means 45 in control of fluid entering and leaving said chamber, visible means for determining the level of the liquid in said chamber and means for returning the liquid to said system subsequent to the withdrawal of said non-condensable gases. 50
